ELASTIC TOP STOCKING AND METHOD OF
PRODUCING THE SAMEHarry McAdams, Reading, Pa., assignor to The
Nolde and Horst Company, Reading, Pa., a
corporation

Application December 21, 1936, Serial No. 117,045

8 Claims. (Cl. 66—173)

This invention relates to improvements in means and method for the knitting of elastic topped stockings.

The primary object of this invention is the provision of an improved elastic topped stocking which simulates somewhat the stocking described in my co-pending application, Serial Number 106,650, filed October 20, 1936, but embodies an improvement thereover in the welt structure 10 which has additional elasticity and increased stability to maintain the stocking properly upon the leg of a wearer.

A further object of this invention is the provision of an improved method for knitting stockings having elastic welts; the method being an improvement over my co-pending application, Serial Number 106,650.

Other objects and advantages of the invention will be apparent from the following detailed description, taken in connection with the accompanying drawings forming a part of this specification and in which drawings—

Figure 1 is a developed view of the needle set-up for the machine, showing the non-elastic and the elastic yarn feeds in position for knitting the welt top of the stocking.

Figure 2 is a fragmentary vertical sectional view taken thru the cylinder of the machine in advance of the regular yarn feed of the machine 30 at the location where an extra elastic yarn is fed to the needles of the machine.

Figure 3 is an enlarged fragmentary view of the fabric which may be knitted upon the machine, showing the relation of stitches both insofar as elastic and non-elastic yarns are concerned thruout the welt, major top and leg of the stocking.

Figure 4 is a side elevation of a stocking such as may be knitted in accordance with the present invention; the stocking having the top adjacent to the welt portion removed to better designate the manner in which the welt is formed.

Figure 5 is a fragmentary developed view of the lug set-up upon a pattern drum of the machine.

Figure 6 is an inside elevation of the additional elastic yarn feed device, also shown in Figure 2.

Figure 7 is an elevation of a stepped cam used with the improved machine in a location which 50 will permit jack actuation at different levels, of jacks having different length butts.

In the drawings, wherein for the purpose of illustration is shown a preferred embodiment of the improved machine and stocking, the letter A 55 may generally designate the knitting machine

which may include a supporting frame B having a cylinder C rotatably mounted thereon. This machine is generally of the type which has been described in my above identified co-pending application, Serial Number 106,650. It may include 5 in addition to the cylinder C a latch ring D having the usual feed fingers thereon at the main feed location, and it also may be provided with auxiliary feed means to be subsequently described. A set of needles E is provided upon the cylinder C. They are independently movable and are provided with a set of control jacks F. The machine may include a pattern drum G and the usual patterning control means associated with knitting machines in conventional use. 15

On the machine the stockings are continuously knitted in stringwork, and are subsequently individually severed and finished to provide a stocking such as shown at H in Figure 4 of the drawings.

As has been described in my above identified co-pending application, Serial Number 106,650, the stocking H of the present invention is also provided with incorporated elastic and inelastic yarns in the top. They are so placed that the top of the stocking will adhere to and conform 20 to the leg of the wearer both circumferentially and longitudinally, in order to efficiently hold the stocking against slipping down upon the leg of the wearer. To that end the inelastic yarn

stitches in the top 10 of the stocking H are knitted appreciably looser than the stitches in the leg portion 11 of the stocking H, by reason of the fact that the stitches are knitted upon a less number of needles of the cylinder of the machine than the number of needles utilized in knitting the leg of the stocking. The elastic yarn thruout the major length of the top 10 is preferably knitted in every other course, or in any course skipped arrangement desired. The top 10 25 of the stocking H has an improved welt arrangement 12 which is relatively deep and formed by folding the top of the stocking upon itself, inside of the top; this inside fold portion of the welt 12 having additional elastic yarn incorporated therein in such a manner as to add to the elastic gripping effect of the welt, without discomforting the wearer; this arrangement being such that the elastic top of the stocking will hold up under constant wear and washing. 30

Referring to the needle set-up shown in Figure 1, the same is relatively the same as the needle set-up shown in Figure 10 of my above identified co-pending application, Serial Number 106,650, except that in the present invention the 35

set-up is such as to permit of the knitting of an additional elastic yarn in the fold in welt portion 12 of the top of the stocking. To that end, at the main feed location the usual heel and toe yarn 13 is used in the knitting of every other course thruout the top of the stocking; the same being fed by a finger 13', operated in the usual manner. At this location it is fed to every third needle of the set E, as shown in Figure 1. These needles receiving yarn 13 are identified on the drawings by numeral 14. At the main feed location an elastic yarn 15 is fed by means of a finger 15' to the same needles 14. These needles 14 are selected by means of a special cam 16; the construction of which will be subsequently set forth when describing the feed of the additional elastic yarn for knitting the fold in welt portion 12 of the stocking. Of course it is understood that the yarn 13 is inelastic, and the yarn 15 is the usual "Lastex." At the main feed location the usual cams 18 are provided to effect the knitting. Wherever cams are shown in the set-up but not described, they are to be considered as conventional and functioning in the usual manner well known to those skilled in the art.

It is to be understood that stockings are knitted in stringwork and the knitting proceeds from the top thruout the leg and then the foot and toe. The connecting portions of the stockings are knitted substantially as described in my above identified co-pending application and the knitting then commences in the fold in welt portion 12 of the next stocking. It is of course understood that the fold in welt 12 is placed in the position shown in Figure 4 by hand after the stockings are severed. However, in this folded portion 12, which in half hose is one inch or more in depth, not only is the elastic yarn 15 provided in each stitch in alternate courses, but an additional elastic yarn 20 is fed by a finger 20' to every tenth needle of the machine, and knitted in together with the stitches formed on those needles by the yarns 13 and 15 at the main knitting cams.

Referring to the jack set-up F, it is noted that jacks 21 are provided below the needles 14 thruout the entire set of needles; these jacks 21 having butts 21' thereon at a predetermined level. Every ninth jack below those needles 14 which are intended to take the elastic yarn 20 has a butt 21'' longer than the butt 21' of the other jacks.

The cam 16 is selectively controlled in the usual manner by levers and mechanism such as has been described in my above identified application, and which is so usual that it need not be further described. It is provided with a stepped portion 16' which engages both the long and short butts 21' and 21'' of the jacks 21, but at the end 25 of the stepped portion 16', the short butts 21' ride off at one level; the longer butts 21'' riding up to the top of the cam 16, as shown in Figure 1. The jacks 21 having the short butts 21' are thus elevated by the cam 16 and force the needles 14 up to a level which will enable the hooks of the needles 14 to take the yarns 13 and 15, but not the elastic yarn 20. However, the longer butts 21'' riding up cam 16 to the full height of the latter push every ninth needle 14 to an elevation above the other needles 14, so as to take the additional elastic yarn 20, as shown in Figure 1.

Referring to Figure 3 of the drawings, the lower portion shows the fold in welt 12 of the top of the stocking and therein are shown stitches

30 formed of the inelastic yarn 13 and which have interknitted therewith stitches 31 formed by the elastic yarn 15. Additionally, in every third stitch wherein the yarns 13 and 15 are knitted the additional elastic yarn 20 is also knitted to form the stitches 32.

Continuing the description of the method of knitting the stocking, it is to be noted that two courses of the stocking are knitted at each revolution of the machine; particularly thruout the top of the stocking. The needles move in the direction indicated in Figure 1 of the drawings, and at the auxiliary feed location of the machine a jack actuating cam 35 is positioned for operation upon the jacks 21. This cam operates on all of the jacks 21 and thus elevates all of the needles 14, that is, every third needle; said needles being elevated as shown in Figure 1 to a location where they may take the inelastic yarn 36. A knitting cam 37 is provided for knitting the yarn 36 upon the needles, and thus form the inelastic yarn courses 40, thruout the top of the stocking; these courses 40 preferably alternating with the courses wherein the elastic yarns are knitted.

As before mentioned, the extra welt elastic yarn 20 is withdrawn after it has been knitted thruout the length of the fold in welt portion 12 of the stocking, and the top 10 is knitted thruout the desired length utilizing the elastic yarn 15 30 in alternate courses.

It is of course understood that because only every third needle of the machine is utilized during the knitting of the top of the stocking, the stitches in the top will be relatively large and 35 loose. The tension on the yarn fed thruout the top of the stocking is not appreciably greater than the tension on the yarn of the leg of the stocking, altho the tension of the elastic yarns fed thruout the top of the stocking is such as to 40 hold the top of the stocking in substantially the appearance shown in Figure 4 of the drawings. Due to the coarseness of the stitches in the top 10 of the stocking, in comparison to the fine stitches thruout the leg of the stocking, the former 45 will present a ribbed effect and will permit ready lateral and longitudinal stretching; the elastic yarns returning the top of the stocking to its original shape and insuring both a circumferential and longitudinal gripping upon the leg of 50 the wearer.

When the course designated at 50 in Figure 3 of the drawings is reached, the yarn 36 is not only fed to every third needle utilized during knitting of the previously knitted courses in the 55 top, but the adjacent needles, normally idle during knitting of the top, are elevated. These adjacent needles designated at 51 in Figure 1 of the drawings, are provided with jacks 52 below them having butts 52' at a different level 60 than the butts of the jacks 21. A cam 54 is provided at a level to act on these butts 52' and elevate the jacks 52 for the purpose of elevating the needles 51 thereabove to a position where they may take the yarn 36 together with the needles 65 14 also elevated at that level. It is only at the auxiliary feed that the needles 51 are elevated. These needles 51 are not utilized in the courses wherein the elastic yarns are knitted. At the auxiliary feed, beginning with the course 50, 70 which forms the juncture between the top of the stocking and the leg, the needles 14 and 51 at the auxiliary feed take the yarn 36 and the stitches caught on the needles 51 are formed into draw stitches in the following manner:

During the same revolution of the cylinder that the needles 14 and 51 are elevated to take the yarn 36, the cam 16 elevates the needles 14 for taking the inelastic and elastic yarns 13 and 15 respectively, and it is noted that the needles 51 are not elevated at this time. Thus, at the main feed block the yarn 36 which is caught on only the needles 14 will cast off and the yarn 36 remains hung on the buried needles 51 until we reach the auxiliary knitting cam 37, where the needles 51 are again elevated to take the yarn 36 and the previous stitches on the needles 51 are cast off to form the draw stitches shown at 60 in Figure 3 of the drawings.

15 It will be noted from Figure 3 that at the juncture of the leg portion 11 with the top 10 of the stocking, the stitches formed are quite closely tucked together to present a neat section without openings. After four courses are knitted at this juncture; producing two rows of draw stitches, as shown in Figure 3, the elastic yarn 15 is withdrawn and all of the needles of the machine are elevated at the regular feed of the machine by the stitch cams acting in the usual manner. Then 20 approximately four courses, shown at 70 in the drawings are knitted, utilizing the inelastic yarn 13. Thereafter, the silk inelastic leg yarn 80 is dropped into action thru its finger 80' and the 25 yarn 13 is withdrawn. The leg yarn is fed to all of the needles of the machine in the ordinary manner.

The stitch cams at the main and auxiliary feeds function in the usual manner.

It will of course be understood that I may 35 depart from the specific arrangement of course placement of the elastic yarns, shown in the drawings, since it is entirely feasible to utilize the elastic yarn in every fourth or every fifth course instead of every other course. It is also 40 quite possible to rearrange the knitting of the elastic yarns in the fold in portion 12 of the welt.

Referring to the finger 20' for feed of the additional elastic yarn 20, as shown in Figures 45 2 and 6 of the drawings, a frame 90 is mounted upon the latch ring D for slidably supporting the finger 20' for vertical reciprocation. A spring 91 normally urges the finger into feed location, as shown in dotted lines in Figure 2. The finger 50 20' is controlled by connecting mechanism 92 off of the pattern drum G.

Referring to the lug layout upon the pattern drum G, the lug arrangement along the dot and dash line indicated at 109 in Figure 5 of the drawings is used to actuate the jack cam 54; the lug arrangement along the dot and dash line 101 is used to actuate the cam shown at 104 in Figure 1 of the drawings; the lug arrangement along the dot and dash line 105 is used to actuate 55 the stitch cam 37; the lug arrangement along the line 107 is used to actuate the elastic yarn finger 20' above described; the lug arrangement along the line 108 is used to actuate the jack dividing cam 16; the lug arrangement along the line 109 is used to actuate a cam 10 provided for lowering 60 every ninth needle which receives the elastic yarn 20, in the relation shown in Figure 1 of the drawings; the lug arrangement along the line 111 is utilized to actuate the cam 35, and the lug arrangement along the line 112 is used to actuate 65 the needle lowering cam 114 shown in Figure 1 of the drawings. This cam 114 lowers the inactive needles, during knitting of the top of the stocking, at the main knitting cam block, 70 so as to avoid the cams of the latter.

The actuation of the elastic and non-elastic yarn fingers, at the main and auxiliary feeds of the machine, is taken care of in the manner set forth in my above identified co-pending application, Serial Number 106,650, filed October 20, 5 1936.

The improved elastic top stocking of the present invention has all of the improved features of the elastic top stocking set forth in my above identified application, and additionally, the inturned 10 welt portion of the stocking is such as to render the top of the stocking more durable and more effective.

Various changes in the shape, size and arrangement of parts, and departure from the steps of 15 the method herein set forth may be made without departing from the spirit of the invention or the scope of the claims.

I claim:

1. As an article of manufacture, a seamless 20 knitted stocking including a top formed of interknitted elastic and non-elastic yarns, the elastic yarn being incorporated in spaced courses of the top, said top having an inturned welt provided with additional elastic yarn incorporated in the 25 courses thereof.

2. As an article of manufacture, a seamless knitted stocking including foot, leg and top portions, the top and leg portions being formed of inelastic yarn with the leg portion having a 30 greater number of wale lines and the stitches of the courses of which are more finely drawn than those of the top portion, elastic yarn interknitted in spaced courses of the top portion, and an additional elastic yarn interknitted in 35 relatively spaced courses at the welt of the top of the stocking.

3. As an article of manufacture, a seamless knitted stocking including foot, leg and top portions, the top and leg portions being formed of 40 inelastic yarn with the leg portion having a greater number of wale lines and the stitches of the courses of which are more finely drawn than those of the top portion, elastic yarn interknitted in spaced courses of the top portion, and 45 an additional elastic yarn interknitted in relatively spaced courses at the welt of the top of the stocking, the said welt wherein the additional elastic yarn is interknitted being inturned upon the top portion to provide a relatively long welt. 50

4. The steps in the method of knitting stockings which includes the feeding of an inelastic yarn to selected needles of a set of needles to provide a top portion, feeding an elastic yarn upon said selected needles together with said 55 inelastic yarn and knitting said yarns together in only occasional courses of the top, knitting together with said elastic yarn and said inelastic yarn a second elastic yarn on said needles in occasional courses of the top directly at the 60 welt thereof, and subsequently feeding inelastic yarns to all of the needles of said set for knitting a leg portion.

5. The steps in the method of knitting a top 65 for seamless stockings which includes the feeding of an inelastic yarn to predetermined spaced needles of a circular set of needles and knitting a top portion therewith, interknitting together with said inelastic yarn an elastic yarn upon said 70 selected needles in only occasional courses of the top portion, and also interknitting together with said inelastic yarn and the first mentioned elastic yarn a second elastic yarn or a less number of selected needles than receive the aforementioned 75

yarns to provide an elastic welt for the top portion.

6. The steps in the method of knitting a stocking or like article having a top portion and a leg portion which includes integrally knitting the leg portion and top portion, with the latter having a less number of wale lines and with the stitches more loosely and coarsely drawn than the stitches formed in the leg portion, and during the knitting of the top portion interknitting an elastic yarn in occasional courses, with a greater number of rounds of elastic yarn directly at the welt at the top portion than elsewhere in the top portion.
7. The steps in the method of knitting a seamless stocking which includes the knitting of the welt of a top portion of the stocking upon only predetermined needles of a set of needles with elastic and inelastic yarns, knitting the remainder

of the top portion upon a greater number of needles but less than the entire number of needles with elastic and inelastic yarns, and knitting a leg portion of the stocking upon all of the needles with inelastic yarn.

8. As an article of manufacture a seamless knitted stocking having a leg portion of inelastic yarn and a top portion of inelastic yarn having fewer wales than the number of wales in the leg portion and with the stitches of the top portion more loosely drawn than the stitches of the leg portion, said top portion having elastic yarn incorporated in the lower section thereof and elastic yarn incorporated in the upper section thereof in a different relation, said elastic yarns being incorporated so as to give to the top portion both a longitudinal and lateral elastic stretch.

HARRY McADAMS.
